DESIGN FOR A PNEUMATIC MOTOR UNIT

John M. Little, Toledo, Ohio

Application June 21, 1943, Serial No. 110,493

Term of patent 14 years

To all whom it may concern:

Be it known that I, John M. Little, a citizen of the United States and a resident of Toledo, in the county of Lucas and State of Ohio, have invented a new, original, and ornamental Design for a Pneumatic Motor Unit, of which the following is a specification, reference being had to the accompanying drawing, forming a part thereof.

Figure 1 is a side elevational view of a pneumatic motor unit, showing my new design; and Figure 2 is a front elevational view thereof.

I claim:

The ornamental design for a pneumatic motor unit, substantially as shown.

JOHN M. LITTLE.
